[57] CLAIM

The ornamental design for a hinge, as shown and described.

DESCRIPTION

FIG. 1 is a perspective view of the hinge;

FIG. 2 is a front view thereof;

FIG. 3 is a top view thereof;

FIG. 4 is a bottom view thereof;

FIG. 5 is a right side view thereof; and,

FIG. 6 is a left side view thereof.

The undisclosed surfaces at the rear of the hinge form no part of the claimed design.

The surface partially obscured by the hinge base at left in FIG. 6 continues the configuration of the sides visible.
